UNITED STATES PATENT OFFICE.

EMIL STRANSKY, OF DOVER, OHIO, ASSIGNOR TO THE DOVER MANUFACTURING COMPANY, OF DOVER, OHIO, A CORPORATION OF OHIO.

THERMOSTAT.

Application filed December 18, 1918, Serial No. 267,320. Renewed November 22, 1920. Serial No. 425,912.

To all whom it may concern:

Be it known that I, EMIL STRANSKY, a citizen of the United States, resident of Dover, county of Tuscarawas, and State of Ohio, have invented new and useful Improvements in Thermostats, of which the following is a specification, the principle of the invention being herein explained and the best mode in which I have contemplated applying that principle, so as to distinguish it from other inventions.

My invention relates to thermostats and particularly to a device of that character which is adapted to control the closing and breaking of an electric circuit. My improved thermostat is applicable for use with a great variety of electrical utilities, such as soldering irons, sad irons, clothes pressing heads, etc., but for the purpose of illustrating the conditions to which my invention is applicable, I shall hereinafter describe the application thereof to a pressing head, further illustrating the application by means of the accompanying drawings.

The annexed drawings and the following description set forth in detail certain means embodying my invention, the disclosed means, however, constituting but one of various mechanical forms in which the principle of the invention may be applied.

In said annexed drawings:

Figure 1 represents a plan view of my invention as applied to a pressing head; Figure 2 represents a transverse sectional view, upon an enlarged scale, taken in the planes indicated by the lines II—II, Figures 1, 4 and 5; Figure 3 represents a fragmentary horizontal section, taken in the plane indicated by the line III—III, Figure 5; Figure 4 represents a fragmentary horizontal section, taken in the plane indicated by the line IV—IV, Figure 5; Figure 5 represents a longitudinal vertical section, taken in the planes indicated by the lines V—V, Figure 4; and Figure 6 represents a diagram of the electric circuit.

Referring to the annexed drawings, a pressing head of standard construction is indicated by the ordinal 1, of which the pressing head member proper is indicated by the ordinal 2. The incoming line of an electric circuit is indicated by the ordinal 3 adapted by a suitable switch to be connected or disconnected with any suitable

source of electric energy. Contained in the circuit is a resistance heating element 4 of any suitable design, the same being suitably disposed adjacent the pressing member 2, as plainly shown in Figure 2, the outgoing element of the circuit from the resistance element 4 being indicated by the ordinal 5. The outgoing terminal of the circuit from the pressing head 1 is indicated by the ordinal 6 connected by the circuit portion 7 with the aforementioned switch. This pressing head 1 is formed with an upstanding peripheral flange 8 and is adapted to support in suitable screw holes 9 formed in upstanding lugs 10 of the pressing head, the usual covering or canopy, not shown. The elements aforementioned are standard and are utilized with the following detail of my invention.

I have formed a chamber 11 in the pressing head 1 and disposed therein a rectangular bed 12 comprised of four side members, as plainly shown in Figure 3, suitable insulation 13 being interposed between the exterior faces of the walls 12 and the walls of the chamber 11. This chamber 11 is of a depth such as to leave approximately $\frac{1}{4}$ " of material between the bottom thereof and the pressing face 2 of the member 1, as substantially indicated in Figure 2. Formed up from the upper face 85 of the pressing head 1 is a second larger rectangular frame 14 covered by a suitable plate 15 secured thereto by means of corner screws 15' and upon one end of this cover plate 15 is mounted a dial 16.

Forming a part of the circuit intermediate the end 5 of the heating element 4 and the outgoing terminal 6 are a pair of copper strips 17 and 19 provided with contact points 18 and 20, respectively, and contact point 18 being adjustable relatively to the strip 17 by means of a screw 18'. The copper strip 19 is in reality comprised of two portions 19 and 19' electrically connected by the circuit portion 6' and mechanically connected by a flexible spring strip 19". This spring strip 19" normally holds the contact points 18 and 20 together and yet allows for their ready separation, as hereinafter fully described.

The strips 17 and 19 are secured at one end upon the two side faces, respectively, of an insulation member 21. Secured to the upper

face of said insulation member 21 by a screw 21² is a plate 22 extended at one end beyond said insulation 21, as plainly shown in Figure 5. A horizontal partition member 23 is secured within the space defined by the frame 12 by means of screws 23' let into interior end shoulders 12' of said frame 12. Said partition member 23 is also formed with vertical posts 25 and 26, plainly shown 10 in Figure 5. The insulation member 21 is formed with a vertical hole 21' intersected by said post 25, a copper sleeve 27 being contained within said hole 21' and surrounding said post 25. Said insulation member 15 21 is supported by a metallic plug 28 upon the partition member 23, the plate 22 and said member 28 being formed with similar vertical holes 21' registering with said aforementioned hole 21', as plainly shown in 20 Figure 5. The upper end of said post 25 is screw-threaded and the elements 21, 22 and 28 are held to place by means of a nut 25' serving as a guide and secured upon said thread. A longitudinally disposed lever 29 25 formed with an elongated transverse slot 30 intersected by said post 25 is secured intermediately of its ends to the projecting end of the plate 22 by a screw 31. One end of said lever 29 is formed with a vertical hole 32 by which said lever is pivoted upon an upper reduced end portion 26' of the post 26. The other and free end of the lever 29 supports a screw 29' intersecting an elongated transverse slot 15² formed in the cover 30 35 plate 15 and supporting at its upper projecting end a button 39. Secured between the cover plate 15 and the button 39 is a pointer 38 adapted to register with the aforementioned dial 16.

40 Disposed within the lowermost portion of the frame 12 and beneath the partition member 23 is a member 33 adapted to be bent proportionately to the amount of heat imparted to the pressing head 1. Said member is comprised of two joined bars 33' and 33² of metal 45 of different coefficients of expansion, whereby said bar 33 will be bent these proportioned amounts. Said member 33 is secured at one end to a member 34 suitably mounted by means of screw 35 upon a boss, not shown, formed up from the bottom of the chamber 11. To the other end of the member 33 is secured a member 36 provided with a vertically extending finger 37 intersecting the 50 slot 24 formed in the partition member 23 and disposed at its upper end adjacent to the circuit strips 17 and 19, a suitable insulation sleeve 36' being mounted upon the top of the finger 37.

55 In the circuit diagram shown in Figure 6, a condenser 40 of standard construction is shown as cut into the circuit by means of circuit connections 41 and 42. A pilot lamp 43 is also shown as cut into said circuit by 60 suitable connections 44 and 45. The use of

the condenser 40 is the standard one of preventing arcing and the pilot lamp 43 may be used when and as desired.

It is evident from the foregoing description and the accompanying drawings that 70 the bending of the member 33, under the influence of the heat imparted to the pressing head 1, will cause the finger 37 carried by said member 33 to intercept the strip 19 and break the connection between the contacts 18 75 and 20. As plainly shown in Figure 2, the lower edge of the strip 17 is formed with a slot 17' whereby the finger 37 may pass said strip 17 without contacting the same. It is further evident from the description and 80 drawings that the circuit strips 17 and 19 can be set or regulated by swinging as a unit, whereby greater or less amounts of bending upon the part of the member 33 will be necessary before the finger 37 contacts with the 85 strip 19 to separate the contacts 18 and 20. Specifically, this regulation is effected through the medium of the button 39 and the screw 29' secured to one end of the lever 29 and adapted to play along the slot 15². 90 It is evident that a movement of the button 39 will cause the lever 29 to move the plate 22, the rear end of the lever 29 being pivoted upon the top of the post 26. Thus through the insulating member 21 secured to the plate 22, the strips 17 and 19 secured to the side faces of the insulating member 21 will be moved, in so far as their contact 95 points 18 and 20 are concerned, in a direction opposite to the movement of the button 39. 100

What I claim is:

1. A thermostat for an electric circuit including a heating element in the circuit, means for making and breaking the circuit comprising relatively movable members, a bar adapted to be moved amounts proportioned to the heating of the element, means for setting or adjusting said circuit making and breaking means as a unit, said means comprising a post suitably supported, a lever pivoted at one end upon said post, fixed intermediate its ends to said circuit making and breaking means, and formed at its other end with an operating button and a pointer, a dial disposed adjacent said pointer and a finger mounted upon said bar and whose path of movement intersects one of the members of said circuit making and breaking means. 110

2. A thermostat for an electric circuit including a heating element in the circuit, two relatively movable circuit making and breaking members included in the circuit, means tending to hold said members normally in contact, a suitable support for said members and insulated therefrom, a lever pivotally mounted adjacent one end and secured intermediate its ends to said members, said lever being insulated from said members, an adjustment button secured to the other end 115 120 125 130

of said lever, and actuating means adapted to be moved amounts proportion to the heating of the element, said actuating means adapted to control the relative movement of said current making and breaking members.

3. A thermostat for an electric circuit including a heating element in the circuit, a bar adapted to be moved amounts proportion to the heating of said element, a finger on said bar, two relatively movable members formed each with a contact point comprising part of said circuit adjacent to said finger, one of said members being comprised of two electrically connected members which are

mechanically joined by a spring normally holding said contact points together, a support for said members, an insulation mounted intermediate said support and said members, a plate mounted upon said insulation, a post suitably supported, and a lever pivoted at one end upon said post secured intermediate its ends to said plate, and formed at its other end with an operating button, the path of movement of said finger intercepting said contact members.

Signed by me, this 7th day of December, 1918.

EMIL STRANSZKY.
